SPOON OR SIMILAR ARTICLE

Melvin A. Lea, Oneida, N.Y., assignor to
Oneida Ltd., Oneida, N.Y.

Filed Dec. 26, 1973, Ser. No. 427,921

Term of patent 14 years

Int. Cl. D7—03

U.S. Cl. D7—137

FIG. 1 is a front view of a spoon showing my new design;

FIG. 2 is a rear view thereof on a reduced scale;

FIG. 3 is a side view thereof on a reduced scale, the undisclosed side being substantially identical with the side shown in FIG. 3;

FIG. 4 is an enlarged cross-section taken on line 4—4 of FIG. 1;

FIG. 5 is an enlarged cross-section taken on line 5—5 of FIG. 1.

I claim:

The ornamental design for a spoon or similar article, substantially as shown and described.
